UNITED STATES PATENT OFFICE.

ISAAC W. EGBERT, OF NEWARK, ASSIGNOR TO WILLIAM B. GOULD, OF MONTROSE, NEW JERSEY.

SPRING-FASTENER FOR TRUNKS.

SPECIFICATION forming part of Letters Patent No. 237,680, dated February 15, 1881.

Application filed December 7, 1880. (No model.)

To all whom it may concern:

Be it known that I, ISAAC W. EGBERT, of Newark, in the county of Essex and State of New Jersey, have invented an Improved 5 Spring-Bolt Attachment for Trunks, of which the following is a specification.

Figure 1 is a face view of my improved spring-bolt attachment. Fig. 2 is a back view of the same. Fig. 3 is a vertical central section thereof, showing the bolt closed; Fig. 4, a similar section showing the bolt open. Fig. 5 is a horizontal section of the same on the line *c c*, Fig. 1.

The object of this invention is to produce a 15 bolt for use near the ends of trunk-lids, which bolt shall be easily unfastened when the trunk is to be opened, easily fastened when the trunk is to be closed, and which will remain in the locked and also in the unlocked position as long as may be desired.

Larger trunks usually have bolts near the ends, independent of the locks, for the purpose of properly uniting the ends of the lid or cover with the ends of the trunk.

25 Heretofore these devices were usually made in the form of spring-hasps, or of catches which will fly shut whenever the trunk is closed, and which, in many cases, had to be specially looked after, even when it was not 30 specially desired to lock the trunk.

My invention consists in the combination of a sliding bolt with a retaining and a receiving socket, and with a spring which will hold the bolt either in the closed or open position, all 35 as hereinafter more fully described.

In the accompanying drawings, the letter A represents the bolt-retaining socket—that is to say, a socket made of suitable material adapted to be fastened to the lid L of the 40 trunk, and in which the bolt B is suspended. C is the receiving-socket, adapted to be fastened below the socket A to the body M of the trunk. These two sockets are in line with each other, as shown in Figs. 1 and 2, and 45 they are made with suitable flanges, which bear against the surface of the lid and body of the trunk to which they are respectively applied, said flanges having suitable holes or other provision to receive fastening-screws, 50 nails, or other devices.

In the interior of the socket C is securely

held a spring, D, which is clearly shown in Figs. 3 and 4. This spring has a backwardly-inclined upper portion, *a*, which is in line with an opening, *b*, that is formed in the face of 55 the socket C.

The bolt B has a head, *d*, at the upper end, and an outwardly-projecting shoulder, *e*, at the lower part. When the bolt is pushed down, (the two sockets being in line and in 60 contact with each other, as in Fig. 3,) so that the head *d* will rest upon the upper end of the socket A, as in Fig. 3, the spring D will crowd the lower end of the bolt outward, so that the shoulder *e* will enter the cavity or 65 aperture *b* and bear against the upper end of said cavity or opening. In this position of parts the bolt locks the two sockets A and C together, and, consequently, also the cover and trunk to which the same are respectively attached.

Now, if the trunk is to be opened, it is only necessary to push the lower part of the bolt inward by inserting the finger through the opening *b*. This backward pressure will cause 75 the inclined back edge, *f*, of the bolt to press against and at the same time ride up on the inclined upper portion, *a*, of the spring D, so that the effect of inserting the finger through the opening *b*, and of pressing the bolt backward, will be to cause the bolt to travel upward into the position shown in Fig. 4. In this position the shoulder *e* will be behind the face-plate of the socket C, and the bolt will no longer interfere with the opening and closing 80 of the trunk, nor will the bolt of its own accord fall shut again. When the bolt is up, a projection, *g*, on the bolt comes under and against an edge, *h*, of the socket A, thus preventing the bolt from flying out in an upward 85 direction. It can only be made to relock the two sockets by pressing the finger upon its upper end and forcing it downward, the spring at the same time forcing the lower end of the bolt outward into the position shown in Fig. 3. 90

It is evident that, although I have shown the bolt-receiving socket C below the socket A, the sockets may be reversed with equal effect, so that the socket C will be above the socket A and the bolt held in the lower socket 100 instead of in the upper.

I claim—

1. The combination of the bolt B, having head d, with the bolt-retaining socket A, and with the bolt-receiving socket C, having opening b, and spring D, whereby the spring will hold the bolt in the locked and also in the open position, substantially as described.

2. The combination of the socket C, having opening b, with the bolt B, having shoulder e and inclined back f, and with the spring D,

having inclined end a, all arranged to operate substantially as described.

3. The combination of the bolt B, having head d, shoulder e, and stop g, with the sockets A C and spring D, as described.

ISAAC W. EGBERT.
